WINDING MECHANISM

Cecil C. McCain, Glen Ellyn, and John W. Hernlund, La Grange, Ill., assignors to Ditto, Incorporated, Chicago, Ill., a corporation of West Virginia

Application May 21, 1934, Serial No. 726,710

18 Claims. (Cl. 242—55)

This invention relates to mechanism for unwinding a band, or the equivalent, from one spindle, or the equivalent, to a second spindle and then rewinding the band, or the equivalent, on the first-mentioned spindle.

The invention is particularly adapted to be embodied in duplicating machines of the hectograph type where the hectograph band is advanced from one spindle to a second spindle over a platen or bed plate, the band being rewound upon the first-mentioned spindle of the hectograph machine whenever it is so desired.

A feature of several forms of the invention is the provision of winding and rewinding means operable by a handle which is always rotated in the same direction whether the hectograph band is being wound upon a spindle or being rewound thereon.

The objects and advantages of the invention will become apparent from the following description, reference being had to the accompanying drawings, wherein—

Fig. 1 is a plan view of a hectograph machine which comprises winding means embodying the invention.

Fig. 2 is a side elevation of the machine shown in Fig. 1.

Fig. 3 is an enlarged section taken on line 3—3 of Fig. 2.

Fig. 4 is a section taken on line 4—4 of Fig. 6.

Fig. 5 is a section taken on line 5—5 of Fig. 4.

Fig. 6 is a section taken on line 6—6 of Fig. 1.

Fig. 7 is a section taken on the same line as Fig. 6 but showing certain parts of the winding mechanism in changed positions.

Fig. 8 is a section taken on the same line as Fig. 6 but showing certain parts of the winding mechanism in changed positions.

Fig. 9 is a section taken through a duplicating machine which has winding means embodying another form of the invention.

Fig. 9A is a section taken on line 9A—9A of Fig. 9.

Fig. 10 is a view similar to Fig. 9 but illustrating certain parts of the winding mechanism in changed positions.

Fig. 11 is a view similar to Fig. 9 but showing certain parts of the winding mechanism in changed positions.

Fig. 12 is a fragmentary section taken on substantially the same lines as Fig. 9 but showing certain parts in section.

Fig. 13 is a fragmentary section taken on the same line as Fig. 12 but showing certain parts in changed positions.

Fig. 14 is a section taken on line 14 of Fig. 12.

Fig. 15 is a section taken on line 15—15 of Fig. 13.

Fig. 16 is a section taken on line 16—16 of Fig. 9.

Fig. 17 is a section taken through winding mechanism which embodies another form of the invention.

Fig. 17A is an enlarged section taken on the line 17A—17A of Fig. 17.

Fig. 18 is a section taken substantially on the same line as Fig. 17 but showing certain parts of the winding mechanism in changed positions.

Fig. 19 is a section taken on substantially the same line as Fig. 18 but showing some parts of the winding mechanism in changed positions.

Fig. 20 is a section taken through the duplicating machine provided with winding mechanism embodying still another form of the invention.

Fig. 21 is a section taken on line 21—21 of Fig. 24.

Fig. 22 is a section taken on line 22—22 of Fig. 21.

Fig. 23 is a section taken on line 23—23 of Fig. 20.

Fig. 24 is a section taken on line 24—24 of Fig. 21.

Figs. 25 and 26 are fragmentary sections taken on the same line as Fig. 24 but showing certain parts in changed positions, and

Fig. 27 is a fragmentary section illustrating a modification of the mechanism shown in Figs. 25 and 26.

Referring for the present to Figs. 1 to 8, inclusive, wherein a preferred embodiment of the invention is illustrated, the reference character 10 designates generally the frame of a duplicating machine of the hectograph type. The machine is provided with a hectograph band 11 which has its ends detachably secured to spindles 12 and 13 at the back and front ends of the frame 10, respectively. The spindles 12 and 13 are preferably identical in construction and are removably mounted in the frame. In Fig. 3, the means for mounting the front spindle 13 is illustrated and as the means for mounting the spindle 12 is of substantially identical construction, a description of the means for mounting the spindle 13 will be sufficient for the purposes of this disclosure. It will be noted that, in this instance, the spindle 13 comprises a tubular body portion 15 which has its ends closed by caps 16 and 16a of identical construction, the ends of the spindle being interchangeable in connection with the means for mounting them. The caps 16 and 16a

are provided with concave recesses 17, the recess 17 of the cap 16a being journaled on a convex surface 18 provided upon one end of a pin 19 which is slidably journaled in a bracket 20 fixed to the frame 10. A spring 22 yieldingly urges the pin 19 against the cap 16a, the movement of the pin 19 in this direction being limited by a pin 23. The caps 16 and 16a are provided with rectangular slots 25 in the bottom portions of the recesses 17. The slot 25 of the cap 16 is engaged by a tongue 27 of a stub shaft 28 which is journaled in the frame 10 and is constrained to rotate with the spiral gear 29. The means for operatively connecting the gear 29 to the stub shaft 28 comprises a pin 30 which projects through the shaft 28 and engages slots 31 in a hub 32 formed integral with the gear 29. The construction is such that while the shaft 28 is constrained to rotate with the gear 29, it may be displaced longitudinally without causing like displacement of the gear 29. The shaft 28 is urged yieldingly toward the cap 16 by a spring 34. A knob 35 secured to the outer end of the shaft 28 provides means whereby the operator may displace the shaft 28 to the left (Fig. 3) against the action of the spring 34 so that the tongue 27 will be withdrawn from the slot 25. When the tongue 27 is withdrawn from the slot 25, it is obvious that the spindle 13 may be removed from the machine. As stated above, similar mechanism is provided for journaling the spindle 12. Thus, in Fig. 1, a knob 35a is shown, the knob 35a having the same function as a knob 35 and providing means whereby the spindle 12 may be released from the machine. In Figs. 2, 6, 7 and 8, the shaft associated with the spindle 12 and corresponding to the shaft 28 is designated by the reference character 28a.

The hub 32 of the gear 29 is journaled in a sleeve 40 mounted in the frame 10.

The gear 29 meshes with a spiral gear 43 formed integral with an elongated tubular hub 44 which is rotatably journaled on sleeves 45 and 46 mounted in a housing 47 fixed to the frame 10 by bolts 48. Rotatably and slidably journaled in the sleeves 45 and 46 and in sleeves 45a and 46a is a shaft 50. The sleeves 45a and 46a are mounted in a housing 47a fixed to the frame 10 by bolts 48a. Rotatably journaled on the sleeves 45a and 46a is an elongated tubular hub 52 which has a spiral gear 53 formed integral with it. Meshing with the gear 53 is a spiral gear 54 with which the shaft 28a is constrained to rotate. The means for constraining the shaft 28a to rotate with the gear 54 comprises a pin 30a which has the same function as the pin 30 and rides in slots 31a cut in a hub 55 formed integral with the gear 54.

It will be readily understood that if the gear 29 is rotated in a clockwise direction (Fig. 6) while the gear 54 is free to rotate, the hectograph band will be unwound from the spindle 12 onto the spindle 13. Also, if the gear 54 is driven in a counter-clockwise direction (Fig. 6) while the gear 29 is free to rotate, the hectograph band will be unwound from the spindle 13 and wound upon the spindle 12. And it will also be understood that if the gears 29 and 54 are driven in clockwise and counter-clockwise directions, respectively, the hectograph band will be drawn taut over a platen or bed 60 forming part of the frame 10. As indicated in dotted lines in Fig. 2, the hectograph band 11 extends from the spindle 12 over the platen 60 to the spindle 13.

The forward end of the shaft 50 is provided with a hub 62 comprising three handles 63, 64 and 65 whereby it may be manipulated by the operator. Three annular grooves 66, 67 and 68 are provided in the shaft 50 adjacent its forward end. A ball 70 is engageable with the grooves 66, 67 and 68, the ball being yieldingly urged toward the shaft 50 by a spring 71 mounted in a bracket 72 fixed to the housing 47. The tension of the spring 71 may be adjusted by a screw 10 73 screw-threaded into the bracket 72. It will be readily understood that the ball 70 will engage the grooves 66, 67 and 68 and retain the shaft 50 yieldingly in the positions wherein it is shown in Figs. 6, 7 and 8. 15

Means is provided for operatively connecting the shaft 50 to the tubular hubs 44 and 52. These means comprise overrunning clutches 75 and 76, respectively. The clutches 75 and 76 are identical in construction and a description of the clutch 75 will be sufficient for the purposes of this disclosure. The clutch 75 is illustrated in detail in Figs. 4 and 5. It will be noted that the clutch 75 comprises balls 78 disposed around the shaft 50 and riding thereon. The balls 78 are 25 retained approximately in the positions wherein they are illustrated in Fig. 4, by a cage 79 having slots 80 which accommodate the balls. The cage 79 is provided with integral prongs 81 which engage grooves 82 formed in the tubular hub 44. 30 The balls 78 engage cam surfaces 84 formed in the tubular hub 44 and springs 85 yieldingly urge the balls 78 into positions wherein they will cause the hub 44 to rotate with the shaft 50 when the shaft 50 is rotated in a clockwise direction (Fig. 4). 35 If the shaft 50 is rotated in a counter-clockwise direction (Fig. 4) the springs 85 will yield and the balls 78 will be displaced in a counter-clockwise direction (Fig. 4) along the cam surfaces 84 in such manner that the hub 44 will not rotate 40 with the shaft 50.

It will be noted that the shaft 50 is provided with annular grooves 88 and 89 associated with the clutches 75 and 76, respectively. The construction is such that when the shaft 50 is displaced from the positions wherein it is shown in Figs. 6 and 7 to the positions wherein it is shown in Fig. 8, the groove 88 will be aligned with the balls 78 of the clutch 75 and rotation of the shaft 50 in either direction will not drive the hub 44. Similarly, when the groove 89 is aligned with the balls of the clutch 76, rotation of the shaft 50 will not drive the hub 52. However, if the gear 29 is driven by the band 11 when the groove 88 is aligned with the balls of the clutch 75, the gear 29 will drive the spiral gear 43 and the hub 44, but this rotation of the hub 44 will not be imparted to the shaft 50. Likewise, if the gear 54 is driven by the band 11 when the groove 89 is aligned with the balls of the clutch 76, the gear 60 55 53 and the hub 52 will be rotated but this rotation of the hub 52 will not be imparted to the shaft 50.

The operation of the apparatus shown in Figs. 1 to 8, inclusive, is substantially as follows: Assuming that the operator wishes to advance the 65 hectograph band 11 over the platen 60 to provide a fresh duplicating surface, it is only necessary to displace the shaft 50 longitudinally until the ball 70 engages the groove 66 as illustrated in Fig. 6. Then if the shaft 50 is rotated in a clockwise direction (Fig. 4) the clutch 75 will drive the hub 44 and the gear 43 and the gear 43 will, in turn, drive the gear 29. The gear 29 will drive the shaft 28 in a clockwise direction (Fig. 6) and the shaft will rotate the spindle 13 in the same 75

direction so that the hectograph band will be withdrawn from the spindle 12 and wound upon the spindle 13. During this operation, the clutch 76 is functionally inoperative as the groove 89 is aligned with the balls of the clutch 76.

After the operator has advanced the hectograph band the desired distance, it is necessary to draw the band taut over the platen. This is accomplished by displacing the shaft 50 longitudinally until the ball 78 engages the groove 67 as illustrated in Fig. 7. The shaft 50 is then rotated in a clockwise direction (Fig. 4) and the clutches 75 and 76 function so that the gears 43 and 53 drive the gears 29 and 54, respectively, the gear 29 being driven in a clockwise direction (Fig. 6) and the gear 54 being driven in a counter-clockwise direction. A partial turn or a slight movement of the shaft 50 is generally sufficient to draw the hectograph band taut.

When substantially the entire hectograph band has been wound around the spindle 13 after a series of duplicating operations, it is sometimes desirable to rewind the band upon the spindle 12 so that the band may be utilized again for a further series of duplicating operations. To rewind the band upon the spindle 12, the operator displaces the shaft 50 longitudinally until the ball 78 engages the groove 68 as illustrated in Fig. 8 whereupon the shaft 50 may be rotated in a clockwise direction which will cause gear 53 mounted on hub 52 to drive the gear 54 in a counter-clockwise direction (Fig. 8). During the rewinding operation, the clutch 75 is functionally inoperative and the clutch 76 is functionally operative.

It will be noted that the spiral gears 43 and 53 are cut in such manner that when they are connected to the shaft 50 through their respective clutches, rotation of the shaft 50 in a clockwise direction (Figs. 4 and 7) will cause the spindle 13 to be driven in a clockwise direction and will cause the spindle 12 to be driven in a counter-clockwise direction.

It will also be noted that the shaft 50 is always rotated in the same direction for the several operations. Thus, in this instance, it is always rotated in a clockwise direction (Fig. 4) during the advancing, stretching and rewinding operations as shown in Figs. 6, 7 and 8, respectively.

It may be mentioned that the duplicating machine has not been fully illustrated as the details thereof do not form a part of this invention.

Referring now to Figs. 9 to 16, inclusive, wherein another form of the invention is illustrated, the reference character 100 designates the frame of a duplicating machine which, with the exception of the winding and rewinding mechanism for the hectograph band, is identical in construction with the duplicating machine illustrated in Figs. 1 and 2. The winding and rewinding mechanism illustrated in Figs. 9 to 16, inclusive, comprises spiral gears 101 and 102 with which shafts 104 and 105, respectively, are constrained to rotate. The means operatively connecting the shafts 104 and 105 to the gears 101 and 102 are identical to the means employed to connect the shafts 28 and 28a to the gears 29 and 54, respectively. Obviously, the shafts 104 and 105 may be displaced longitudinally relative to the gears 101 and 102 so that the front and back spindles (not shown) of the duplicating machine may be removed as explained in connection with the duplicating machine shown in Figs. 1 and 2.

The hectograph band for the duplicating machine illustrated in Fig. 9 is designated by the

reference character 106. It will be readily understood that the hectograph band 106 may be advanced to the front spindle (not shown) by rotating the gear 101 in a clockwise direction (Fig. 9) and that the band may be rewound upon the back spindle (not shown) by rotating the gear 102 in a counterclockwise direction (Fig. 9). It will also be readily understood that the band 106 may be tightened over the platen of the duplicating machine by simultaneously rotating the gears 101 and 102 in clockwise and counterclockwise directions, respectively, (Fig. 9).

The gears 101 and 102 mesh with spiral gears 108 and 109, respectively, the gears 108 and 109 being provided with elongated tubular hubs 110 and 111, respectively. Projecting through the tubular hubs 110 and 111 is a shaft 115 which corresponds to the shaft 50 described above and is provided at its forward end with a handle 116 which is preferably identical in construction with 20 the handle illustrated in connection with the shaft 50.

The shaft 115 is rotatably and slidably journaled in sleeves 118, 119, 120 and 121 (Figs. 10 and 11). The sleeves 118 and 119 are fixed in a 25 housing 123, which corresponds to the housing 47 described above. The sleeves 120 and 121 are fixed in a housing 124 which corresponds to the housing 47a described above. The hub 110 has one end rotatably journaled on the sleeve 118. 30 One end of the hub 111 is rotatably journaled on the sleeve 120.

Interposed between the shaft 115 and the hubs 110 and 111 are overrunning clutches 130 and 131, which correspond to the clutches 75 and 76, 35 respectively, described above and are identical of construction. It will be noted that the shaft 115 is provided with annular grooves 134 and 135 which are associated with the overrunning clutches 130 and 131, respectively. The construction is such that when the groove 134 is not aligned with the clutch 130, rotation of the shaft 115 in the direction indicated by the arrow 137 in Fig. 9 will cause the clutch 130 to drive the gear 108 in the same direction and the gear 108 45 will drive the gear 101 in a clockwise direction (Fig. 9). If the shaft 115 is rotated in the same direction while the groove 135 is not aligned with the clutch 131, the clutch 131 will rotate the gear 109 in the same direction and the gear 109 will 50 rotate the gear 102 in a counter-clockwise direction (Fig. 9). If the groove 134 is aligned with the clutch 130, the band 106 may be unwound from the front spindle (not shown) without causing the gears 101 and 108 to drive the shaft 115. 55 Similarly, the band may be unwound from the back spindle (not shown) without causing the gears 102 and 109 to drive the shaft 115 if the groove 135 is aligned with the clutch 131.

A spring 140 disposed around the shaft 115 and 60 interposed between the sleeve 119 and a collar 141 fixed to the shaft 115 yieldingly urges the shaft 115 to the left (Fig. 9).

Disposed in an annular groove 143 formed in the hub 110 is a ring 144 to which the bifurcations of a bifurcated lever 145 are operatively connected. The lever 145 is pivoted on a pin 146 disposed between the bifurcations and a handle 147 formed on the upper end of the lever 145. It will be noted that the major portion of the lever 70 145 is disposed within the frame 100 but that the handle portion projects through a slot 148 formed in the frame. The lever 145 may be displaced from the position wherein it is shown in Fig. 9 to the position wherein it is shown in 75

Fig. 11 so that the hub 110 and the clutch 130 will be displaced to the left (Fig. 11). The lever 145 is held in the position wherein it is shown in Fig. 11 during the rewinding operation. It will be noted that the groove 134 is then aligned with the clutch 130 and rotation of the shaft 115 in the direction of the arrow 137 will not cause the clutch 130 to drive the hub 110.

As best shown in Figs. 9 and 9A, the handle 147 is provided with a ball 147a which rides in a bore 147b formed in the handle 147. A spring 147c yieldingly urges the ball 147a to the right (Fig. 9A). The ball 147a is adapted to engage two depressions 147d and 147e formed in a plate 147f fixed to the frame 100. When the ball 147a engages the depression 147d, the lever 145 is retained yieldingly in the position illustrated in Fig. 9. When the ball 147a engages the depression 147e, the lever 145 is retained yieldingly in the position indicated in Fig. 11. The spring 147c yields readily when the operator displaces the lever 145 from one position to the other.

Secured to the front wall of the housing 123 is a cam member 150 which co-operates with a cam member 151 rotatably journaled on the shaft 115 (Figs. 12 to 15, inclusive). The cam members 150 and 151 are provided with co-operating cam surfaces 152 and 153, respectively, which are of such conformation that the cam members may nest in the manner illustrated in Fig. 12. Also, the cam surfaces 152 and 153 are of such conformation that if the cam member 151 is displaced by rotating the shaft 115 through 90° in a direction opposite to that indicated by the arrow 137, the cam member 151 will ride up on the cam member 150 so that the cam member 151 will be displaced to the right (Figs. 12 and 13), which displacement will be accompanied by a like displacement of the shaft 115 as the shaft 115 is operatively connected to the cam member 151 by a pin 155 which projects from a hub 156 into an annular groove 157 formed in the shaft 115. The hub 156 is formed integral with the cam member 151. The cam members 150 and 151 are provided with teeth 159 and 160, respectively, which engage each other when the cam members are in the position wherein they are illustrated in Fig. 13. It will be noted that when the cam members are in the positions wherein they are illustrated in Fig. 13 the teeth 159 and 160 prevent the cam member 151 from being displaced in the direction indicated by the arrow 162 (Fig. 13). However, the teeth 159 and 160 do not prevent rotation of the cam member 151 in the direction opposite to that indicated by the arrow 162.

The handle 116 is splined to the shaft 115 by a key 165. The handle 116 is provided with an enlarged hollow hub 166, the hub 166 being provided with an outwardly extending flange 167 disposed between the frame 100 and a ring 169 secured to the frame 100 by screws 170 (Figs. 12 and 13). The ring 169 permits the hub 166 to rotate around the longitudinal axis of the shaft 115 but prevents displacement of the hub 166 and the handle 116 in directions toward or away from the frame 100.

Pivoted on a pin 173 fixed in the hub 166 is a pawl 174 which is engageable with a ratchet 175 formed integral with the hub 166 and, therefore, with the cam member 151.

The operation of the apparatus shown in Figs. 9 to 16, inclusive, is as follows: When the band 106 is to be withdrawn from the back spindle

(not shown) and wound upon the front spindle (not shown), the apparatus is adjusted as illustrated in Fig. 9. The operator then rotates the handle 116 and the shaft 115 in the direction indicated by the arrow 137. In other words, if the machine is viewed from the front thereof, the operator rotates the handle 116 and the shaft 115 in a clockwise direction. Such rotation of the shaft 115 causes the clutch 130 to drive the hub 110 and the gear 108 so that the gear 101 is rotated in a clockwise direction (Fig. 9). As the groove 135 is then aligned with the clutch 131, the back spindle, the shaft 105, the gear 102 and the gear 109 rotate yieldingly and permit the band 106 to be unwound from the back spindle and wound upon the front spindle. When the handle 116 is rotated in the direction of the arrow 137, the pawl 174 simply rides over the teeth of the ratchet 175 as the pawl is rotated bodily in a clockwise direction (Fig. 14) around the longitudinal axis of the shaft 115.

After the hectograph band 106 has been advanced the desired distance, the operator rotates the handle 116 and the shaft 115 in a direction opposite to that indicated by the arrow 137 and through an angular distance of 90° or more, whereupon, the pawl 174 engages a tooth of the ratchet 175 and causes it to rotate the ratchet and the cam member 151 through the same angular distance so that the cam 151 rides up on the cam 150 as illustrated in Fig. 13. The apparatus is then adjusted as illustrated in Fig. 10 so that when the operator rotates the shaft 115 in the direction indicated by the arrow 137, the clutches 130 and 131 will drive the hubs 110 and 111. The gears 108 and 109 will then drive the gears 101 and 102 in clockwise and counter-clockwise directions, respectively, so that the band 106 will be stretched taut over the platen of the duplicating machine. Of course, the spiral gears 101, 102 and 108 and 109 function as locking means when the operator ceases to rotate the handle 116 and lock the back and front spindles against rotation in either direction until the shaft 115 is rotated again. The similar spiral gears of the apparatus shown in Figs. 1 to 8, inclusive, function in the same manner. It will be noted that the shaft 115 has been displaced to the right in Fig. 10 and that the spring 140 has been compressed.

When the operator desires to rewind the band upon the back spindle of the duplicating machine, the apparatus is adjusted as shown in Fig. 11. The operator moves the lever 147 into the position wherein it is shown in Fig. 11 so that the groove 134 is aligned with the clutch 130. Then when the handle 116 and the shaft 115 are rotated in the direction of the arrow 137, the clutch 131 rotates the hub 111 and the gear 109 in the same direction so that the gear 102 rotates in a counter-clockwise direction (Fig. 11). This rotation of the gear 102 causes the back spindle (not shown) to wind the band 106 around it.

If the operator subsequently desires to advance the band to the front spindle (not shown), the handle 116 and the shaft 115 are rotated in a direction opposite to the direction indicated by the arrows 137 and 162 (Figs. 9 and 13, respectively) and the cam member 151 is displaced through an angle of 90° so that the spring 140 will displace the shaft 115 to the left (Fig. 11) and nest the cam members 150 and 151 so that they will assume the positions wherein they are illustrated in Fig. 12. Of course, the lever 145

is returned to the position wherein it is shown in Fig. 9.

Referring now to Figs. 17 to 19, inclusive, wherein another form of the invention is illustrated, the reference character 200 designates a duplicating machine which, with the exception of the mechanism for winding and rewinding the hectograph band, is identical in construction with the duplicating machine illustrated in Figs. 1 and 2. The gears 201 and 202 shown in Figs. 17 to 19, inclusive, correspond to the gears 29 and 54, respectively, and are connected to the front and back spindles, respectively, of the duplicating machine illustrated diagrammatically in Figs. 17 to 19, inclusive. The means for connecting the gears 201 and 202 to the front and back spindles (not shown) is identical with the similar means in Figs. 1 to 8, inclusive, and need not be illustrated or described in detail.

The gears 201 and 202 mesh with spiral gears 203 and 205, respectively, which are provided with elongated hubs 206 and 207, respectively. The gears 201, 202, 204 and 205 are disposed within housings 209 and 210 secured to the frame 230, the housing 209 being associated with the gears 201 and 204 at the front end of the machine. Sleeves 212, 216, 213 and 217 are fixed in the housings 209 and 210, respectively, and rotatably and slidably journal a shaft 215.

Spined to the forward end of the shaft 215 is a handle member 220 which is preferably identical with the handle member 116 shown in Figs. 9 to 11, inclusive. A bifurcated member 221 fixed to the frame 230 engages a groove 222 formed in a hub 223 formed integral with the handle member 220. The bifurcated member 221 prevents the handle 220 from being displaced away from or toward the frame 230.

Disposed in the hubs 206 and 207 are overrunning clutches 225 and 226, respectively, which are identical in construction with the clutch devices 75 and 76 described above. Annular grooves 228 and 229 formed in the shaft 215 are associated with the clutch devices 225 and 226, respectively. The construction is such that if the grooves 228 and 229 are not aligned with the clutch devices 225 and 226, respectively, when the shaft 215 is rotated in the direction indicated by the arrows 230 (Figs. 17, 18 and 19) the clutch devices will drive the hubs 206 and 207 in the same direction. However, if the annular groove 228 or 229 is aligned with its associated clutch device when the shaft 215 is rotated in the direction indicated by the arrows 230, the clutch device 228 or 229 having its associated groove aligned with it will be functionally inoperative and will not drive the corresponding gear 204 or 205. Rotation of the shaft 215 in a direction opposite to that indicated by the arrows 230 will not cause the clutch devices 225 and 226 to drive the gears 204 and 205, respectively.

A collar 240 rotatably journaled on the shaft 215 is held against relative displacement longitudinally of the shaft by collars 241 and 242 which are pinned to the shaft 215. Pins 244 projecting from the collar 240 ride in slots 245 provided in the bifurcations of a bifurcated lever 247 which is pivoted intermediate its ends by a pin 248 projecting from the frame 230. The lever 247 is provided with a handle 249 whereby the operator may displace it around the pin 248.

As best illustrated in Fig. 17A the lever 247 is provided with a boss 250 having a recess 251 in which a ball 252 is slidably journaled. A

spring 253 disposed in the recess 251 yieldingly urges the ball 252 toward a boss 255 formed upon the frame 230. The boss 255 is provided with three recesses 256, 257 and 258 engageable by the ball 252 when the ball 252 engages one of the recesses 256, 257 or 258 to yieldingly retain the lever 247 in that position.

The operation of the apparatus illustrated in Figs. 17 to 19, inclusive, is as follows: Assuming that a hectograph band 260 is to be unwound from the back spindle (not shown) and wound upon the front spindle (not shown), the apparatus is adjusted as shown in Fig. 17 so that the ball 252 engages the recess 258 and the groove 228 is aligned with the clutch device 226. The operator then rotates the handle 220 and the shaft 215 in the direction indicated by the arrows 230 whereupon the clutch device 225 drives the gear 204 through the hub 206. The gear 204 drives the gear 201 in a clockwise direction (Fig. 17) and the gear 201 rotates the front spindle (not shown) so that the hectograph band 260 is withdrawn from the back spindle (not shown) and rewound upon the front spindle (not shown). During this operation, the gears 202 and 205 are free to rotate as the clutch device 226 is functionally inoperative.

After the operator has advanced the hectograph band the desired distance, the lever 247 is displaced until the ball 252 engages the recess 257, whereupon the apparatus will be adjusted as illustrated in Fig. 18. It will be noted that in Fig. 18, the grooves 228 and 229 are not aligned with the clutch devices 225 and 226, respectively. When the operator then rotates the shaft 215 in the direction indicated by the arrows 230, the clutch devices 225 and 226 rotate the gears 204 and 205 so that the gears 201 and 202 will be rotated in clockwise and counter-clockwise directions, respectively, (Fig. 18). This operation will stretch the band 260 taut across the platen of the hectograph machine. When the operator ceases to rotate the shaft 215, the helical gears 201, 204, 202 and 205 will serve as locking means to prevent the spindles (not shown) from unwinding the hectograph bands.

When the operator desires to rewind the hectograph band 260 upon the back spindle (not shown) associated with the gear 202, the lever 247 is displaced so that the ball 252 engages the recess 256. The apparatus is then adjusted as illustrated in Fig. 19 so that the clutch device 225 is functionally inoperative when the shaft 215 is rotated in the direction of the arrows 230. The operator then rotates the handle 220 and the shaft 215 in the direction of the arrows 230 and the clutch device 226 rotates the hub 207 and the gear 205. The gear 205 then rotates the gear 202 in a counter-clockwise direction (Fig. 19) so that the hectograph band 260 is withdrawn from the front spindle (not shown) and rewound upon the back spindle (not shown).

Still another form of the invention is illustrated in Figs. 20 to 26, inclusive. Referring first to Fig. 20, the reference character 300 designates generally the frame of a hectograph machine which, with the exception of the mechanism for winding and rewinding the hectograph band, is substantially identical in construction with the hectograph machine shown in Figs. 1 and 2. The winding and rewinding mechanism comprises gears 301 and 302 which correspond to the gears 29 and 54, respectively, of the winding and rewinding mechanism illustrated in Figs. 1 to 8, inclusive. The gears 301 and 302 are operatively

connected to the front and back spindles, (not shown) respectively, by mechanism which is identical with the mechanism by which the gears 29 and 54 are connected to the back and front spindles of the machine shown in Figs. 1 to 8, inclusive, therefore it is not necessary to give a further description of this mechanism. The gears 301 and 302 mesh with spiral gears 304 and 305, respectively, the gear 305 being pinned to a shaft 306 and the gear 304 being pinned to a sleeve 307 which is rotatably journaled on the shaft 306 and in a housing 308. The housing 308 encloses the gears 301 and 304. A similar housing 310 encloses the gears 302 and 305. The back end 15 of the shaft 306 is journaled in the housing 310.

As best shown in Fig. 24, the hub 311 of a ratchet 312 is pinned to the forward end of the sleeve 307. A second ratchet 313 is splined to the shaft 306 by a key 314. A hand wheel 315 is rotatably journaled on a hub 317 formed integral with the ratchet 313. A collar 319 pinned to the hub 317 prevents displacement of the ratchet 313 longitudinally of the hand wheel 315. The hand wheel 315 is provided with a boss 320 from which a handle member 321 projects, the handle member 321 being provided with a cylindrical boss 322 which is slidably and rotatably journaled in the boss 320. Formed integral with the boss 322 is a pin 323 provided with cam members 324 and 325. The cam members 324 and 325 are provided with frustro-conical cam surfaces 326 and 327, respectively. The cam surfaces 326 and 327 cooperate with pawls 329 and 330, the pawl 329 being engageable with the ratchet 313 and the pawl 330 being engageable with the ratchet 312. Springs 332 and 333 yieldingly urge the pawls 329 and 330, respectively, toward the ratchets 313 and 312, respectively. Disposed around the pin 323 and interposed between the cam member 324 and a shoulder 335 formed in the boss 320, is a spring 337 which yieldingly urges the cam members 324 and 325 to the left (Figs. 24, 25 and 26). When the parts are adjusted as illustrated in Fig. 24, the cylindrical boss 322 of the handle member 321 abuts 40 against a shoulder 338 formed in the boss 320, these parts being held in these relative positions by the spring 337.

As best illustrated in Figs. 23 to 26, inclusive, a bell crank lever 340 is pivoted to the boss 320 by a pin 341. The bell crank lever 340 comprises arms 342 and 343 which are accommodated in a slot 344 formed in the boss 320. The frame 342 is provided with a finger piece 346. A spring 348 yieldingly urges the bell crank lever 340 in a clockwise direction (Fig. 23). The arm 342 has a latch portion 350 adapted to engage either side of an annular flange 351 forming part of the cylindrical boss 322. It will be noted that the bell crank lever 340 may be displaced from the position wherein it is shown in full lines in Fig. 23 to the position wherein it is shown in dotted lines in the same figure so that the latch portion 350 will be withdrawn from the path of the annular flange 351.

65 The operation of the apparatus illustrated in Figs. 20 to 26, inclusive, is as follows: Assuming that the operator wishes to advance the hectograph band 355 from the back spindle (not shown) to the front spindle (not shown) the apparatus is adjusted in the manner illustrated in Fig. 24. The operator then rotates the hand wheel 315, through the medium of the handle member 321, in a clockwise direction (Fig. 21) so that the pawl 330 will rotate the ratchet 312, the sleeve 307 and the gear 304 in the same direc-

tion. Such rotation of the gear 304 will cause it to rotate the gear 301 in a clockwise direction (Fig. 20) so that the hectograph band 355 will be withdrawn from the back spindle (not shown) and wound upon the front spindle (not shown). 5

The shaft 306 will not be rotated by the hand wheel 315 during this operation, but it will be rotated in a counter-clockwise direction (Fig. 21) through the medium of the gears 302 and 305 which will be rotated as the back spindle (not 10 shown) is rotated by the withdrawal of the hectograph band therefrom. Of course, the ratchet 313 will rotate in a counter-clockwise direction with the shaft 306 during this operation.

When the hectograph band 355 has been advanced the desired distance, the mechanism may be adjusted for the stretching operation by pulling the handle member 321 into the position wherein it is shown in Fig. 25 against the action of the spring 337. It will be noted that in Fig. 25 the 20 flange 351 abuts the left hand side of the bell crank lever 340 and it will also be noted that the cam surfaces 326 and 327 are disposed in positions wherein they permit the pawls 329 and 330 to engage the ratchets 313 and 312, respectively. 25 During the stretching operation, the operator retains the handle member 321 in the position wherein it is illustrated in Fig. 25 while the hand wheel 315 is being rotated in a clockwise direction (Fig. 21). A partial turn of the hand wheel 315 30 causes the ratchet members 313 and 312 to drive the sleeve 307 and the shaft 306 in a clockwise direction (Fig. 21). The gears 301 and 302 are then driven in clockwise and counter-clockwise directions, respectively, (Fig. 20) to stretch the 35 band. When the band has been stretched the desired amount, the operator simply releases the handle member 321, whereupon it returns to the position wherein it is shown in Fig. 24 and may be utilized directly thereafter to again advance 40 the hectograph band.

When the operator desires to rewind the hectograph band 355 upon the back spindle (not shown), the bell crank lever 340 is first brought into the dotted line position wherein it is illustrated in Fig. 23 and the handle member 321 is brought into the position wherein it is shown in Fig. 26. The lever 340 is then returned to its initial position so that the spring 337 will hold the flange 351 against the right side (Fig. 26) of 50 the lever 340. When the parts are arranged as in Fig. 26, the pawl 330 is held in a position wherein it can not engage the ratchet 312, the pawl 329 being in engagement with the ratchet 313. During the rewinding operation, the operator simply revolves the hand wheel 315 in a clockwise direction (Fig. 21) which will cause the ratchet 313 to rotate the shaft 306 in a clockwise direction (Fig. 21). Such rotation of the shaft 306 will cause the spiral gear 305 to rotate the 60 gear 302 and the back spindle (not shown) in a counter-clockwise direction (Fig. 20). The back spindle (not shown) will then withdraw the band 355 from the front spindle (not shown) and wind the band upon itself. During this operation, the 65 gears 301 and 304, as well as the ratchet 312, are free to rotate. After the rewinding operation, the handle member 321 may be restored to the position wherein it is illustrated in Fig. 24 whereupon it may be utilized to advance the gelatin 70 band as desired to the front spindle (not shown).

In Fig. 27, alternative construction is shown for the hand wheel 315 and the handle member 321. In Fig. 27 the handle member is designated by the reference character 321a and the hand 75

wheel is designated by the reference character 315a. The handle member 321a is provided with a pin 323a which is slidably and rotatably journaled in a boss 320a formed integral with the hand wheel 315a. The pin 323a is provided with cam surfaces 326a and 327a which correspond to the cam surfaces 326 and 327, respectively, and co-operate with pawls 329a and 330a. The pawls 329a and 330a co-operate with the ratchets 313a and 312a, respectively, which have the same functions as the ratchets 313 and 312.

The pin 323a has three annular grooves 400, 401 and 402 engageable by a ball 405 slidably journaled in a bore 406 formed in the boss 320a. A spring 408 disposed in the bore yieldingly urges the ball 405 toward the pin 323a. The tension of the spring 408 may be adjusted by a set screw 410. It will be readily understood that when the ball 405 engages one of the grooves 400, 401 or 402, the ball will yieldably retain the pin 323a in that position. The construction is such that when the ball 405 engages the groove 402, the hand wheel 315a may be rotated to advance the hectograph band to the front spindle (not shown). When the ball 405 engages the groove 401, the hand wheel 315a may be rotated to stretch the hectograph band and when the ball 405 engages the groove 400, the hand wheel 315a may be rotated to rewind the hectograph band upon the back spindle (not shown). In each instance, the hand wheel 315a is rotated in the same direction.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as permissible, in view of the prior art.

We claim:

1. Apparatus for unwinding a band from either of two spindles, or the equivalent, and winding it upon the other, said apparatus comprising a rotatable member, means operatively connecting said rotatable member to one of said spindles to wind the band thereon when said rotatable member is rotated in a predetermined direction, and means operatively connecting said rotatable member to the other of said spindles to wind the band thereon when said rotatable member is rotated in said predetermined direction, and control means for both the aforesaid means operable to cause them to simultaneously connect both said spindles to the rotatable member, whereby rotation of said member draws the band taut between said spindles.

2. Apparatus for unwinding a band from either of two spindles, or the equivalent, and winding it upon the other, said apparatus comprising a shaft, gears with which said spindles are constrained to rotate, gears on said shaft meshing with the first-mentioned gears, and means controlling said gears to cause them to wind the band upon one of said spindles when said shaft is rotated in a predetermined direction and for causing said gears to wind the band on the other of said spindles when said shaft is rotated in said predetermined direction said means including mechanism for causing said gears to turn both spindles from said shaft at once.

3. Apparatus for unwinding a band from either of two spindles, or the equivalent, and winding it upon the other, said apparatus com-

prising a shaft, gears with which said spindles are constrained to rotate, gears on said shaft meshing with the first-mentioned gears, and overrunning clutches operatively connecting said gears on said shaft to said shaft together with control means for simultaneously rendering both clutches operative to connect their respective gears to the shaft to draw the band taut between said spindles upon further rotation of said shaft.

4. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, and clutch devices interposed between said shaft and said third gear and between said shaft and said fourth gear, said clutch devices being responsive to longitudinal movements of said shaft to render them functionally inoperative.

5. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, and clutch devices interposed between said shaft and said third gear and between said shaft and said fourth gear, said clutch devices being responsive to longitudinal movements of said shaft to render them functionally inoperative and said shaft and clutch devices having cooperating portions operating, in one position of said shaft, to connect both the third gear and the fourth gear to said shaft to rotate both the spindles simultaneously to wind the ends of the band thereon.

6. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, and clutch devices interposed between said shaft and said third gear and between said shaft and said fourth gear, said clutch devices being responsive to longitudinal movements of said shaft to render them functionally inoperative and said clutch devices being operative to rotate either of said spindles selectively to wind the band thereon, said shaft being rotated in the same direction in each instance.

7. Apparatus for unwinding a band from either of two spindles, or the equivalent, and winding it upon the other, said apparatus comprising a gear with which one of said spindles is constrained to rotate, a second gear with

- which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, a handle for rotating said shaft, means for displacing said shaft longitudinally, and clutch devices interposed between said shaft and said third gear and between said shaft and said fourth gear, said clutch devices being responsive to longitudinal movements of said shaft to render them functionally inoperative.
15. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, a handle splined on said shaft for rotating it, means for displacing said shaft longitudinally, and clutch devices interposed between said shaft and said third gear and between said shaft and said fourth gear, said clutch devices being responsive to longitudinal movements of said shaft to render them functionally inoperative.
9. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, a handle for rotating said shaft and displacing it longitudinally, and clutch devices interposed between said shaft and said third gear and between said shaft and said fourth gear, said clutch devices being responsive to longitudinal movements of said shaft to render them functionally inoperative.
10. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, means slidably and rotatably journaling said shaft whereby said shaft may be displaced longitudinally relative to said third and said fourth gears, clutch devices interposed between said shaft and said third gear and between said shaft and said fourth gear, said clutch devices being responsive to longitudinal movements of said shaft to render them functionally inoperative, and means for displacing one of said clutch devices longitudinally of said shaft while said shaft remains in a fixed position with respect to the first-mentioned gear.
11. Apparatus for unwinding a band from either of two spindles, or the equivalent, and winding it upon the other, said apparatus comprising a gear constrained to rotate with one of said spindles, a

second gear constrained to rotate with the other of said spindles, a shaft, a sleeve disposed around said shaft, a third gear fixed to said sleeve and meshing with the first-mentioned gear, a fourth gear fixed to said shaft and meshing with said second gear, a ratchet with which said sleeve is constrained to rotate, a second ratchet with which said shaft is constrained to rotate, a rotatable member, pawls carried by said rotatable member and engageable with said ratchets, and means for controlling said pawls whereby either of said pawls may be held disengaged from its associated ratchet.

12. Apparatus for unwinding a band from either of two spindles, or the equivalent, and winding it upon the other, said apparatus comprising a gear constrained to rotate with one of said spindles, a second gear constrained to rotate with the other of said spindles, a shaft, a sleeve disposed around said shaft, a third gear fixed to said sleeve and meshing with the first-mentioned gear, a fourth gear fixed to said shaft and meshing with said second gear, a ratchet with which said sleeve is constrained to rotate, a second ratchet with which said shaft is constrained to rotate, a rotatable member, and pawls carried by said rotatable member to simultaneously engage said ratchets and drive said sleeve and said shaft in the same direction, said gears operating to wind the ends of said bands on said spindles when said shaft and said sleeve are driven in the same direction.

13. Apparatus for unwinding a band from either of two spindles, or the equivalent, and winding it upon the other, said apparatus comprising a gear with which one of said spindles is constrained to rotate, a second gear with which the other of said spindles is constrained to rotate, a shaft, a third gear on said shaft meshing with the first-mentioned gear, a fourth gear on said shaft meshing with said second gear, clutch devices interposed between said shaft and said third gear and between said shaft and said fourth gear, said clutch devices being responsive to longitudinal movements of said shaft to render them functionally inoperative, and means slidably and rotatably journaling said shaft whereby said shaft may be displaced longitudinally into any one of three predetermined positions.

14. Apparatus for winding a band from one of two spindles, or the equivalent, and winding it upon the other, said apparatus comprising a rotatable member, means operatively connecting said rotatable member to one of said spindles to wind the band thereon when said rotatable member is rotated in a predetermined direction, and means operatively connecting said rotatable member to the other of said spindles and co-operating with the first-mentioned means and said rotatable member to rotate the spindles in opposite directions simultaneously to stretch said band.

15. Apparatus for winding a band from one of two spindles, or the equivalent, and winding it upon the other, said apparatus comprising a rotatable member, means operatively connecting said rotatable member to one of said spindles to wind the band thereon when said rotatable member is rotated in a predetermined direction, and means connecting said rotatable member to the other of said spindles and co-operating with said first-mentioned means and said rotatable member, when said rotatable member is rotated in said predetermined direction, to rotate the spindles in opposite directions simultaneously to stretch said band.

16. Apparatus for winding a band from one of

two spindles, or the equivalent, and winding it upon the other, said apparatus comprising a gear with which one of said spindles is constrained to rotate, a second gear with which the other of said spindles is constrained to rotate, a third gear meshing with the first-mentioned gear, a fourth gear meshing with said second gear, and means for simultaneously rotating said gears to rotate the spindles in opposite directions whereby said band will be drawn taut between the spindles.

17. Apparatus for winding a band from one of two spindles, or the equivalent, and winding it upon the other, said apparatus comprising a gear with which one of said spindles is constrained to rotate, a second gear with which the other of said spindles is constrained to rotate, a third gear meshing with the first-mentioned gear, a fourth gear meshing with said second gear, and means

including a shaft for rotating said third and said fourth gears simultaneously to rotate said spindles in opposite directions.

18. Apparatus for winding a band from one of two spindles, or the equivalent, and winding it upon the other, said apparatus comprising a gear with which one of said spindles is constrained to rotate, a second gear with which the other of said spindles is constrained to rotate, a third gear meshing with the first-mentioned gear, a fourth gear meshing with said second gear, and means including a shaft and clutch devices for rotating said third gear and said fourth gear to rotate said spindles in opposite directions whereby said band will be drawn taut between said spindles. 15

CECIL C. McCAIN.
